UNITED STATES PATENT OFFICE.

JOHN C. EPENETER, OF DENVER, COLORADO.

ADDING AND SUBTRACTING MACHINE.

No. 856,236.

Specification of Letters Patent.

Patented June 11, 1907.

Application filed July 14, 1906. Serial No. 326,248.

To all whom it may concern:

Be it known that I, JOHN C. EPENETER, a citizen of the United States of America, residing at the city and county of Denver and State of Colorado, have invented a new and useful Adding and Subtracting Machine, of which the following is a specification.

My invention relates to improvements in adding and subtracting machines.

10 The object of this invention is to provide improved mechanism for locking the depressed numeral keys, and which will at the same time prevent the depression of other keys in the same row in which a key has been depressed, the pressure of the said key unlocking a spring-actuated rack, which when the operating handle is pulled, will recede a number of intervals or steps, corresponding to the number on the depressed key; the said 15 racks carrying pivoted type bars, which are tripped by suitable mechanism as the racks recede, causing the said bars to strike a recording sheet and record the number of the key depressed, while at the same time the 20 racks which have receded turn a corresponding number of accumulating wheels, a number of teeth corresponding to the number of the depressed key.

A further object of the invention is to provide 25 interchangeable adding and subtracting mechanisms, which are operated by the same accumulating wheels, one set being in operative relation to the wheels, while the other set is inoperative, and means for causing the racks to engage the wheels, on their rearward movement, when adding, and on their forward movement, when subtracting, the said adding and subtracting mechanisms being arranged to advance the tens wheel one 30 step, when the units wheel has been moved ten steps, the hundreds wheel one step when the tens wheel has been moved ten steps, and so on to the last wheel; the invention further 35 contemplating the employment of improved means for shifting the type-ribbon at right angles to the axis of the platen roll, and for simultaneously turning the said roll, with its record sheet, and one of the ribbon spools, each a predetermined distance, said movements being accomplished at each movement 40 of the operating lever.

The invention further consists in numerous minor details of construction, all of which are fully set forth in the accompanying specification and claims.

In the accompanying drawings, Figure 1,

is a side elevation of my improved machine, the casing thereof being in section. Fig. 2, is a central, vertical, longitudinal sectional view of the same. Fig. 3, is a plan view of 6c the machine, the casing being in section. Fig. 4, is a vertical, transverse, sectional view on the line 4—4 of Fig. 1. Fig. 5, is a detail perspective view, illustrating the type keys, the locking plates, the lock-plate 65 latches, and mechanism for operating them. Fig. 6, is a rear view of the machine, the casing being in section. Fig. 7, is a view of a row of keys from 1 to 9, arranged in the order in which they operate in the machine, but 70 turned with their front sides outward, in order to show the construction of their lower ends. Fig. 8, is a perspective view of one of the key-locking plates, in a reverse position to those shown in the other views, for the 75 purpose of clearer illustration. Fig. 9, is a perspective view of one of the sliding racks, carrying one of the pivoted type bars, and showing the stepped arrangement of one of its members, by which it engages and is 80 stopped by the lower ends of the keys. Fig. 10, is a perspective view of one of the rack 85 levers, which support the adding and subtracting mechanism, and other parts. Fig. 11, is a perspective view of one of the pull levers, which effect the lifting of the accumulating gears out of engagement with the sliding racks. Fig. 12, is a perspective view of the subtracting mechanism, which is operated by the accumulating wheels, the adding 90 mechanism being similar, but arranged to be operated from the other sides of the wheels. Fig. 13, is a perspective view of one of the sliding bars with its trip lever, latch, and pawl lever, detached from the adding mechanism. Fig. 14, is a perspective view of the latch shown in the above view. Fig. 15, is a view showing the mechanism for turning the platen roll and shifting the ribbon. And Fig. 16, is a plan view of a portion of the casing of the machine, showing the mechanism for moving the ribbon at right angles to the axis of the platen roll.

Similar letters of reference refer to similar parts throughout the several views.

Referring to the drawings, the numeral 1, in general, designates the supporting casing of my invention. This casing consists of the floor 2, the front end 3, the rear end 4, and the sloping top 5, and the straight top 6. The straight top is provided with an opening 7, centrally above which I revolvably mount

in bearings 8, a platen roller 9, the lower side of which projects into the opening 7, and below the under side of this roller axially with its length and close to it, I support a type-writing ribbon 7A, preferably a two color ribbon, from two ribbon-holding spools 10 and 11, which are rotatably mounted in brackets depending from the top of the casing in position to feed the ribbon to and under the roller. The ribbon spools are operated in the same manner as in the ordinary type-writing machine, the spool shafts being provided with bevel gears 10A, which are operated by similar gears 10B on a shaft 10C, which may be shifted so that one of its gears 10B may engage one of the ribbon spool gears, while its opposite gear 10B is out of engagement with the adjacent ribbon spool gear, as will be understood. This 20 sliding shaft 10C also carries a broad faced ratchet wheel 10D, which is engaged by mechanism to be hereinafter described, to effect the rotation of the said shaft, and a paper roll 9A, is supported in standards rear of the platen roll, in position to allow the paper to be passed between the ribbon and platen roll.

Below the roller and its ribbon, I arrange a plurality of type bars 12, seven being illustrated, though a greater number may be employed if desired, and these type bars are pivotally connected to upward extensions of a similar number of sliding racks 16, one of which is shown in Fig. 9. The top edge of 35 each type bar, is provided with a raised tongue of metal 13, which engages one end of a spring 14, the opposite end of which is connected to the sliding rack 16, to which the said type bar is pivotally attached, and this 40 spring is fulcrumed at 17A, as shown. The type bars 12, are pivotally secured near their forward ends by pins 18, to the sliding racks 16, which racks comprise vertical members 17, which extend from the bottom of the casing to the top thereof, the lower ends of 45 which terminate in rearwardly extending portions 18A, upon the top edges of which gear teeth 19, are formed, and forwardly extending arms 19A, the upper edges of which 50 are stepped as shown at 19B, nine of these steps being employed to form a corresponding number of shoulders, the purpose of which will presently appear. The forward end of each type-bar, is provided with a 55 downwardly extending hook portion 12A, which are adjacent to the ends of rock arms 20, which are positioned to stand horizontally, said rock arms being pivotally mounted on a shaft 21, the opposite ends of which 60 are pivotally mounted in brackets 21A, which are secured to the top of the casing and depend therefrom. The arms 20 are in the form of bell cranks, and their depending members have apertures 22, in which are secured the ends of coiled springs 23, the oppo-

site ends of which are secured to a pin 24, which is also supported in the brackets 21A. The horizontal portions of the arms 20, are provided with recesses in their under sides, which are engaged by the ends of fingers 25, that project from the upright members of the sliding racks. Across the casing in front of the sliding rack, I mount in slots formed in the casing a cross-bar 28, which is normally held against the sliding racks by springs 26, as will be presently explained. This cross-bar 28, is secured to a pair of arms 29, the opposite ends of which are slotted as shown at 30, and are connected to a pair of actuating levers 31, by pins 32, which pass through the slots 30A. To the cross bar 28, is secured a number of spring dogs 27, corresponding to the number of type bars, the free ends of which are formed with upwardly extending hooks, and these hooked ends extend between the racks and normally contact with the under edges of the arms 20, in position to engage the ends 12A of the type bars when the arms 20 are lifted by the fingers 25 the purpose of which will be fully explained hereinafter.

The rock arms 31, stand in a vertically disposed position, and their lower ends are secured upon the opposite ends of a shaft 33 which is journaled in bearings 34, secured to the bottom and sides of the casing. This shaft 33 extends beyond the casing on the right hand side, and upon this extended end secure a hand operating lever 35 (see Fig. 4) which is used to impart a predetermined forward movement to the levers 31, which produces a corresponding movement of the cross bar, permitting the racks to recede an the dogs 27, to engage the type bars, as will be more fully explained hereinafter. Before the lever 35, is operated however, it is necessary to release the sliding racks 16, as they are held normally locked, and I will now describe the mechanism by which they are held normally locked and also the mechanism by which they are released.

The number keys 15, are arranged in several parallel rows lengthwise of the machine, and each row of keys is numbered respectively from one to nine. The lower ends of the keys are all on the same horizontal plane, but each row or tier of keys from right to left is longer than the row immediately preceding it, the length of each preceding tier of keys being determined by the incline of the top of the casing. Thus the tiers extend one above the other in step by step order, and they are supported in operative position by the top of the casing, and by a depending plate 34, the casing and plate being provided with slots through which the keys pass. These keys extend vertically down through the slots in the casing and plate, and terminate normally at a short distance above locking devices 36, which I term lock plates. The

lock plates 36, are substantially L-shaped in cross section, and are hinged by trunnions to the casing at one end, and to a bracket 36^a at their opposite end. These lock plates stand with their lower limbs normally in a horizontal plane, and the lower ends of the keys normally stand a short distance above them, and in line with their outer edges. The lower end of each key stem is reduced in width to form a shoulder 37, and these shoulders are on the same plane as the upper ends of the lock plates, and adjacent to them. The key stems preferably comprise narrow rods, and at the lower end of each stem on the opposite side from the shoulder 37, a lateral stop lug 38, is formed. These stops in each row of keys from 1 to 9, are arranged relatively to the steps 19B on the arms 19A of the racks 16, the stops of the first tier of keys, or those representing the numeral 1, being in position when the keys are depressed, to receive the forward end of the arms 19A, so as to permit them to move forward only one interval, while the stops of each succeeding tier of keys when depressed will be in position to stop the rack at the stop or interval corresponding to the number of the depressed key. Above the shoulders 37, and on the same side of the key stem, notches 39 are formed, and the vertical limb of the lock-plate is formed with a right-angled hook edge 40, which is adapted to fit loosely in the notches 39 of each key-stem, when a key is depressed, the notches being so positioned relatively to the hook 40, that when a key contacts with a lock plate, the notch will be in line with the said hook. Thus whenever any key in any row is pushed down, its terminal stem strikes the lock plate and tilts it, thus causing the vertical arm of the lock plate to tilt toward the side of the key stem, and its hook 40 to move into the notch 39, in the side of that particular key-stem that has been pushed down, but the hook is so positioned relative to the remainder of the key-stems of that row, that when the hook of the lock plate is thrown forward it moves under the shoulders 37 of all of the other keys in that row and locks them against being pressed down. A spring 41, is connected to the forward end of each lock plate, and to the casing, and these springs normally hold the lock plate in the position shown in Figs. 4 and 5, the ends of the lock plates engaging stops 42, which define the upward movement of the said plates.

When a lock plate is tilted down by depressing a key, it is locked in that position by a latch 43, one being employed for each plate, and these latches are pivotally mounted on a shaft 44, which is supported in the opposite sides of the casing. The lower ends of the latches lie in recesses 45, formed in the forward ends of the lock-plates, as shown in Fig. 5, and these ends have notches 46, which

normally stand on a slightly lower plane than the adjacent edges of the recesses 45, so that when the plates are depressed or tilted, they will be engaged by the notches 46, and held until the latches are moved to release them, as will be further explained. The upper ends of the latches are formed with rearwardly-extending projections, to which contraction springs 47 are attached rear of the pivot rod 44, the opposite ends of which are secured to the casing. These springs exert a pull on the latches and cause their notches to engage the lock plate, as previously described.

Upon the projections at the upper ends of the latches rests a rod 48, the opposite ends of which are secured to the forward ends of a pair of arms 49, the opposite ends of which are pivotally secured to a rod 50, the ends of which are mounted in the opposite sides of the casing. The arms 49 have vertical extensions 51, the upper ends of which are in the form of a T, and each T lies in the path of a pair of sliding bars 52 and 53, which are operated by the vertical levers 31, as will be explained fully hereinafter. The inner bars 52, of each pair, I term pull bars, and the outer bars of each pair I term push bars. These bars are of the form shown in Fig. 11, and extend to the rear end of the machine, the rear ends of the bars being slotted, as shown at 54, to engage circumferential guide grooves in pins 55, secured to the sides of the casing, and which support the rear ends of the bars. As the bars are pulled forward, their full distance, their ends come in contact with the T arms 51, pushing them forward a short distance and moving rod 48 downward, on the extensions of latches 43, which tilts them, and unlocks the lock plates 36, as will be more fully explained hereinafter.

I will now describe the mechanism that co-operates with the keys 15 to release the sliding bars, so that when the hand operating lever 35, is drawn toward the operator, the type bars and their co-operating mechanism will be put into operative printing relation to print on the paper of the paper feeding roll. The keys are all held in their respective operative positions relative to each other, by springs 56, their being one spring for each key stem. The forwardly extending ends 19A, of the sliding racks 16, extend to within a short distance of the first tier of key-stems, or those bearing the number 1, which distance is equal to the interval between any two of the type faces on the type bars 12, which are pivoted to the racks or between two of the teeth on the said rack. In the ends of the forward extensions 19A, of the sliding racks, I form slots 57, which extend into the ends parallel with their length, a distance equal to the whole distance traveled by a rack, when a 9 key is depressed. The top edges of the forwardly extending bars 19A,

of the sliding rack, are provided with nine vertical face step portions, as above described, and the forward ends of these extensions are one interval or tooth distant from the ends of first tier of keys, or those bearing the number 1. These steps are arranged in the following order: The first vertical faces of the first steps are positioned relatively to the terminal ends of the second tier of keys a distance equal to the travel of two teeth, or two-ninths of the full travel of the racks; the second steps are placed from the ends of the third tier of keys a distance equal to the travel of three teeth, or three-ninths of the full movement of the racks, and the vertical faces of the third steps are placed from the ends of the fourth tier of keys a distance equal to the travel of four teeth, or four-ninths of the full travel of the racks; and so on to the ninth key-stem. Thus when a number nine key is pressed, the sliding rack 16 must move the type-bars far enough forward to bring the type numeral nine on the type-bars under the ribbon and platen roller. The stop lugs 38 on the lower ends of the keys are placed in the path of the step corresponding to the number of the key depressed, so that when any key is depressed the sliding rack and the type-bar connected with that rack are moved forward far enough to bring the corresponding type numeral of the type-bar under the ink ribbon and platen roller, and this is accomplished by springs 58, which are connected at their ends to the racks and to a shaft 59, that extends across the casing and is supported in the sides thereof. Grooved rollers 60, are mounted on this shaft for the extensions 19A to rest and slide on, and the springs 58 hold the sliding-racks under a constant forward pulling tension. They are all held back in normal inoperative position however, by lugs 61, which are formed on the horizontal edge of each lock plate, and which engage the terminal end of the extensions 19A, of the sliding racks just above the slots 57 (see Fig. 4). When any one key-stem is depressed, and the lock-plate is tilted, this lug is moved down into the entrance of the slot 57, and the sliding rack is released; but is held against forward movement by the cross bar 28, until the hand operating lever 35, is drawn forward, which permits the spring 58, to draw the rack forward until stopped by the depressed key, when a further movement of the lever 35, and of the cross bar, will trip the type-bar and print the numeral corresponding to the key depressed, in the manner and by mechanism to be now fully described.

The type keys are numbered from 1 to 9, but the type bars are numbered from 0 to 9, and the line of zeros or naughts stand normally below the ribbon. The type bars are held in their normal position by their springs 65 14. When one or more of the keys are de-

pressed, as in adding, the corresponding lock plates are tilted, the corresponding racks are unlocked, and the operating handle is moved forward to impart a similar movement to the cross bar 28, which permits the unlocked racks to be drawn forward by their springs 58, until stopped by the depressed keys. But as the racks start forward, their fingers 25, which lie beneath the rack arms 20, will lift them, and allow the spring dogs 27, to engage the ends 12A of the type bars, until the racks are stopped by the keys; when a further movement of the cross bar will cause the spring dogs 27, to pull upon and tilt the type bars, when the dogs will escape, thus tripping the type bars, which will be thrown up against the platen roll by their springs, with sufficient force to print the numerals represented by the depressed keys. The two springs 26, which return the cross bar, and simultaneously the racks, must exert a pulling tension, considerably greater than the combined tensions of the seven springs 58, which operate the racks, in order that the racks may be instantaneously returned to their normal position, after all the type bars have been tripped and the numbers printed.

In order to print the naught, each rock arm 20, beginning with the one on the units side of the machine, is provided with a lip 20A, which extends over and rests upon the adjacent arm to the left; thus, should any one of the arms be lifted, all the arms to the right of it would be lifted also. For example: if it is desired to print 9000, the nine key in the thousands row is depressed, and the rack in that row is thereby unlocked, while all the other racks remain locked. The operating handle is then moved forward, and the unlocked rack moves forward also, its finger 25, lifting the rack arm above it, which in turn lifts the one to the right of it, and so on to the last arm, thus permitting the spring dogs 27, to engage the ends 12A of the type bars, and as the racks are locked, the type-bars to the right of thousands bar will be tripped immediately after the cross bar starts forward, and print the three naughts simultaneously, while the "thousands" rack will continue to the limit of its movement before its type bar is tripped.

The slots 30 in the arms 29, attached to the cross bar 28, permit the rock arms 31 to move forward a predetermined distance before their movement is transmitted to the cross bar, and this is to enable other mechanism connected with the rock arms 31, and which will be presently described, to begin their operation before the cross bar is moved. The pivot pins 32, connecting the arms 31 and 29, are thus at the outer ends of the slots, when the cross bar begins its movement, and as the cross bar is thrown quickly back to its normal position, by its springs 26, when the operating handle is released, its im-

pact upon the racks would also throw the arms 31 still farther forward the distance of the length of the slots 30 in the arms 29, and the arms would rebound to the opposite end 5 of the slot again, and in order to prevent this, and to keep the arms at the limit of their rearward movement, I connect the arms 31 and cross bar 28, by springs 31A, which, when the operating handle is released, will 10 immediately draw the arms 31 to the rear ends of the slots 30, and keep them there after the cross bar strikes the racks.

I will now describe the adding and subtracting mechanism. Adjacent to the sides 15 of the casing, I place a pair of levers 62, see Fig. 2 both of which are provided at their rear ends with depending extensions 63 and 64, the latter resting on the floor of the casing. The forward ends of these two levers 20 are curved downward slightly and are pivotally mounted on the shaft 59. Through the rear ends of these levers centrally between their depending extensions, I form in each a journal aperture in which I mount a shaft 65, 25 on which is rotatably mounted seven gears 66, one for each of the seven toothed racks, and I position them on the shaft so that each gear is in mesh with its adjacent toothed rack. I provide each gear with a hub that projects 30 from opposite sides of it, of a length sufficient to permit each hub to bear against the hub of the adjacent gear, and the hubs of the end gears extend to and bear against the sides of the levers 62. The gears are thus all held in 35 alignment with the racks, while the racks are held in operative position by the rollers 60, which are mounted on the shaft 59, and by rollers 67, which are mounted on a rod secured in the sides of the casing, there being 40 one of each of these rollers 60 and 67 for each sliding rack.

Upon the left hand side of each gear at four equidistant points in its circumference, and close to the base of the teeth, I place pins 45 68, which extend laterally out from the side of the gears a short distance. These pins are adapted to engage the downwardly sloping edges of trip levers 69, that project into the path of the pins of each gear, and are each 50 pivotally connected to one of a group of seven vertically sliding bars 70, which are housed in a cage comprising side bars 71, and end plates 72. See Fig. 12. There are two of these cages 73 and 74, one on each 55 edge of each gear, and they are similar in construction and have similar levers. The cage 73 houses the adding mechanism and the cage 74 houses the subtracting mechanism. The top or upper ends of these end plates of 60 both cages are provided with pins 75, which extend over the upper edges of the levers 62, to receive connecting rods, as will be shown later. These two cages and their groups of levers are positioned on opposite sides of the 65 group of gear wheels, and directly over the

toothed racks, and are arranged and adapted to be interchangeably operated by said gear wheels, depending on whether sums are to be added or subtracted, to carry the numeral above nine from one gear to the other. The 70 end plates 72 of both of these cages, are pivotally secured at their lower ends to the lower ends of the depending extensions 63 and 64 of the levers 62.

The pins 75, of the end plates of both cages, 75 are connected to the opposite ends of connecting rods 76, which connect the cages together. To one of these connecting rods I pivotally connect one end of a rod 77, the opposite end of which extends forwardly in the 80 path of a rock arm 78, which is secured to a shaft 79, that is pivotally mounted in the opposite sides of the casing. To this shaft is rigidly secured seven right angle levers 80, which are all depressed by a single key 81, 85 which may be secured to one of the levers 80 or to a separate lever 82, as shown in Fig. 3. I term this key the total key. The free ends of these seven right angle levers depend toward and are adapted to engage the lock 90 plates 36, and unlock all of the type keys, as will be explained hereinafter. The rod 77 is pivotally connected intermediate of its ends to a rock arm 83, which is mounted on a rod 84, which extends across the casing, and is 95 pivotally journaled in its sides. On the opposite end of the shaft 84, I secure a rock arm 85, which is similar to the rock arm 83, and these rock arms are each provided with a pair of horizontally disposed fingers, which are adapted to bear against the under sides of the two pairs of levers 52, 53, which I term push and pull levers, one lever in each pair being a push lever, while the remaining lever in each pair is a pull lever and the arms 83 and 85, 105 are tilted by springs 84A in the position shown in Fig. 1, to allow the pull levers 52, to normally engage the pins 87 to the rock arms 31. These two pairs of levers are positioned on opposite sides of the casing, and the rock 110 arm 31 on one side of the casing passes up between the two levers on that side, while the rock arm on the opposite side of the casing passes up between the levers on that side.

Each lever 52, 53, is recessed on its under edge, as shown at 86, and each arm 31, is provided with a pin 87, which projects from each side of it, and these pins engage the recesses 86 of the levers 52, 53, to pull one pair or push the other pair, according as they are raised or lowered by the rock arm 83, and 85 either to be engaged by the pins 87, or to be out of engagement with them. The pins 87 of the arms 31, are formed with upward projections which prevent the rods 52, 53, from slipping off the said pins. On one side of each of the pull levers 52, I pivotally secure an arm 98, and these arms I term lifting arms. These lifting arms are pivoted at their lower end to the lower edges of the levers, and project up 130

and forward at an angle of about 45 degrees, to the shaft 65, which carries the gear wheels 66. The arms 98 are held normally against stop pins 99, by springs 100 (see Fig. 11). 5 The push levers 53, are provided on one side with lifting arms 101, which are also pivoted at their lower ends, and are caused to incline toward the rear end of the casing by springs 102. The upper ends of the arms 98 and 101, 10 are cut off so as to be parallel with and on the same plane with the top edges of the levers 52, 53, and upon these ends of the lifting arms are pivotally secured spring-actuated latches 98A, and 101A, respectively, which act in conjunction with the ends of the lifting arms, to 15 engage the shaft 65, and lift the gear wheels out of engagement with the racks. The dogs on the lifting arms of the pull levers, have a forward movement, being held against the opposite movement by a stop 98B, which engages the front edge of the said lifting arm. Thus, when the lever is pulled forward, the end of the arm and dog will engage the shaft 65, and lift it, so as to disengage the gear 20 wheels from the racks, but when the lever returns, the dog will be depressed, and the end of the lifting arm will pass beneath the shaft 65, which escaped the lifting arm, and dropped into its normal position; when the 25 pull levers reached the limit of their forward movement.

The dogs 101A on the lifting arms of the push levers, move in the opposite direction from the dogs 98A, and their stops 101B engage the rear edges of the arms. Thus, 30 when the push levers are moved forward, they are inoperative and the dogs on their lifting arms pass under, and then engage the shaft 65, so that when the push levers move rearward the shaft is raised, as in the previous manner. The arms as soon as they engage the shaft swing upward as the pull levers move forward, until they pass their vertical centers, and as the pull levers still continue 40 forward, the shaft drops down, thus letting the gears down again into mesh with the toothed rack, which occurs the instant the operating handle 35 reaches the end of its stroke, and the arms 98 as soon as they escape the shaft are drawn forward by the contraction springs 101, which are secured to them and to the levers.

In order to define the operative position of the arms 98, I place stop pins 99 in the levers 45 against which the arms are normally held by the contractive tension of the springs 101, and the push levers are provided with stop pins 101C, which limit the rearward movement of arms 101, though as shown in Fig. 1, 50 these arms rest against the guide pins 55, until the arms move some distance forward. As the push levers must be inoperative, or 55 out of engagement with the pins 87 of the rock arms 31, when the pull levers are operative or in engagement with the aforesaid pins,

and vice versa, means must be employed for connecting one set and disconnecting the other set simultaneously, and this feature of my invention I carry out in the following manner:

To one of the connecting rods 76, of the cages, see Fig. 1 preferably the right hand rod, I pivotally secure one end of a lever 103, which I term a subtracting lever; this lever is a vertically positioned lever and extends up through a slot in the top of the casing. It is rigidly mounted on a rod 104, which extends across the casing and is secured in its sides, and near the opposite end of this shaft I secure one end of a lever 105, the opposite end of which I connect to the connecting rod 76 on the ends of the cages; consequently the cages have two of these levers, one on each side; though the right hand lever 103, only, extends through the top of the casing. When this subtracting lever stands at the forward end of the slot, the adding mechanism which is contained in the cage 73 is in engagement with the gear wheels 66, but when this subtracting lever is manually moved to the opposite end of the slot it moves the two cages 73 and 74, toward the forward end of the casing, putting the adding mechanism, which is housed in the cage 73, out of engagement with the gear wheels, and the subtracting mechanism which is housed in the cage 74, into engagement with the gear wheels, and this forward movement of the cages is imparted to the rod 77, which being attached to the rock arm 83 moves it and the corresponding arm 85, lifting the pull levers 52 off the pins 87 of the arms 31, and allowing the push levers to drop down on the said pins. The forward end of the rod 77 is now adjacent to the lower end of the depending arm 78, and acts as a stop to prevent the total key 81 from being pressed down, and consequently to prevent a total being taken while the subtracting lever and the subtracting mechanism is in operative engagement with the gear wheels. The upper end of the depending arm 78, is rigidly connected to the shaft 79, and adjacent to this arm, and upon the said shaft 79, is rigidly secured an upwardly extending arm 106, the free end of which is pivotally connected to one end of a lever 107, which is pivotally connected to the rock arm 83, and its adjacent end extends beyond this pivotal connection with the rock arm, and is pivotally connected to one end of a lever 108, the opposite end of which is pivotally connected to a rod 109, which is supported by the outer ends of two cranks 110, which are secured on a rod 111, that extends across the casing and is secured in its sides. These two rods 109 and 111, are positioned directly above the sliding bars 70, of the adding mechanism, and the rod 111 is engaged by these sliding bars 70, on the upward movement of the adding cage 73, at the rear end of 125 130

the levers 62, as they are raised by the push and pull levers, causing the levers 62 to swing upward on the shaft 59, to which they are pivotally connected. The object of bringing the bars 70 in contact with the rod 111, is to return them to their normal position in the cage 73, after they have been thrown up by the action of the gears 66, and their pins 68, as will now be shown.

- 10 The vertical sliding bars 70, are mounted in vertical recesses, formed in the inner sides of the two side bars 71, of the cages 73 and 74, and at their lower ends they are provided with vertical slots 112, which straddle annular grooves that are formed on a shaft 113, that extends from one end plate 72 to the other, and are secured to them. To the lower ends of each of these vertical sliding bars I pivotally secure the lower end of a
- 15 trip latch 114, the upper ends of which are provided with shouldered steps, the vertical part of which rests against the outside bars 71, while its horizontal faces extend under the lower edge of side bars and are held up against them by contraction springs 115, which are secured to notches 116 in the lower ends of the trip latches, and to rods 117 that are secured at their ends in the levers 62. A spring extends from each of these latches to
- 20 the rods, and holds their notched upper ends against the under side of the side bars of the cage, and each of these latches is disengaged from the side bars of the two cages by the trip levers 69, which are provided on their sides opposite those engaged by the pins 68 of the gears, with projecting dogs 118, and these dogs lie across the back edges of the trip latches at a short distance from them, when in normal position, so that when a trip
- 25 lever is pushed out by a pin on the engaging gear it will throw the latch out of engagement with the bar 71, and the sliding bar, trip lever, and latch will be thrown up by the spring 115. Each trip latch is also provided
- 30 with a laterally extending arm 119, which is positioned to lie below the trip lever, and extends to the next or adjacent trip lever, and terminates on a line with its dog, so that the arm 119 of each trip latch, beginning at the
- 35 right, extends to but below the dog of the adjacent trip lever, as will be seen by reference to Fig. 12; the first trip lever at the right being the units lever in each cage and mechanism, and the next lever the tens, and so on to the last lever.

On the opposite side of each sliding bar from the trip lever, in each cage, and below their pivotal end, I pivotally secure pawl levers 120, the lower ends of which are curved outward and downward, and extend in close proximity to the teeth of the gears, but lie in front of rods that extend across the casing, and are connected to its sides, the rod for the adding cage being numbered 121, while that

65 for the subtracting cage is numbered 122,

and these rods normally prevent the pawl levers from engaging the gears. From the side of these levers just above their curved ends, right angled pawl extensions 123, are formed, which extend from their said levers to the adjacent gear on the left, commencing with the units pawl lever (see Fig. 3). Thus, for example, when the units wheel has been moved nine points or teeth, one of its pins 68, will contact with the adjacent trip lever 69, 75 and a further movement of the wheel one point will push out the trip lever, which will, through its dog, release the adjacent latch 144, and permit the sliding bar to which it is attached, to fly up. The operating lever is 80 drawn forward, and the pull levers 52, will lift all of the gears, their shaft, the cages, and the supporting arms or levers 62, as previously described, and the projecting sliding bar 70 will contact with the rod 111, which 85 will restore it to its normal position in the cage, and as it is forced down by the said rod 111, the pawl 123, of the pawl lever 120, will engage the "tens" wheel and move it one interval, or tooth, and in this way the adding 90 of a unit to the next order is accomplished. Now, if the "tens" wheel had also been moved nine points or teeth, only, previously to the units wheel, the trip lever of the "tens" sliding bar would be pushed out against its 95 trip latch, but would not release it, consequently when the "units" latch flies up, its arm 119 will be forced between the dog of the "tens" trip lever and its latch, thus forcing the "tens" latch out and allowing the "tens" 100 sliding bar to fly up also, and as this bar also contacts with the rod 111, its pawl lever will move the "hundreds" wheel one step, thus carrying 1 from the tens to the hundred, after which its curved lower end will contact 105 with the rod 121, and move it out of engagement with the gear wheel.

The adding mechanism is normally in position to be operated by the gears (see Fig. 2), but the subtracting mechanism can only 110 be used by first operating the subtracting lever.

After a type-key, say the type key No. 9, of the units column, has been depressed, the operating handle 35 is moved forward to the 115 full limit of its stroke, and during the first part of its stroke raises the shaft 65, and its gears and the cages and their supporting levers 62, thus raising the gears out of mesh with the racks and allowing the units rack to 120 move forward nine teeth, and then at the end of the forward stroke of the operating lever, the gears again drop down into engagement with the racks. The operating lever is then thrown rearward to the end of its 125 back or return stroke by the springs 26, and this movement returns the units rack to its normal position, and rotates the units gear nine teeth, thus registering on the units gear the nine that has been printed on the paper. 130

Then if it is desired to add one or more to the nine, say for example 1, the No. 1 type-key of the unit row of type-keys is depressed, the same as the No. 9 was, and the operating lever is again moved forward, but this time the unit rack moves forward but one tooth, it being stopped by the stop on the No. 1 key, as has been above described, but the operating lever still moves forward to the end of its operative stroke, and in doing so again raises the gears through the medium of the pull levers as above described, and when the operating lever is reversed or moved back on its rearward stroke the gears all drop down again into engagement with the racks, and the units rack moves back one tooth and rotates the units gear one tooth, and in moving this one extra tooth one of the pins 68 has engaged the beveled edge of the trip lever 69, and moved the dog 118 on its opposite end against the unit trip-latch, which movement throws the trip-latch off of the side bar 71 of the cage 73. The trip-lever and the units vertical sliding bar and pawl lever are thrown upward by the contraction spring 115, the distance of one tooth, so as to bring the pawl arm of the pawl-lever out into the tooth of the next or tenths gear, in position to move that gear one tooth, when the operating handle is again moved forward, which movement will accumulate on the tens gears one unit additional to nine, or a total of ten, and complete one cycle of the printing and adding operation of the machine. The units sliding bar 70, will now stand directly in front of the rod 109, and will thus prevent the total key from being depressed, until after the operating handle has again been pulled forward, this rod 109 being connected with the total key shaft 79, by arms 107 and 108. But in order to make a total of these two numbers, it is necessary to again operate the operating lever 35, to return the units vertically sliding levers of the adding cage to its nominal position, and when this is done the vertical sliding lever which was thrown up, with its pawl lever and trip levers by the spring 115, are held up by this spring, until moved down by the upward movement of the cages against the rod 111, by the movement of the operating lever 35, and its pull rods, as has been before described. Consequently as the cage and the gears raise up, the pawl of the pawl lever of the unit sliding lever, which is in engagement with a tooth of the tenths gear, rotates the tens gear one tooth as the gear moves upward, thus completing the registering of the total ten, on the units and tens gears. And to print a total of this amount and to return all of the gear wheels to zero, I proceed as follows: I press and hold the totaling key down, which action through the medium of the right angled levers 80 releases all of the lock plates 36, and actuates the

arm 107 to tilt the rock arms 83 and 85, the fingers of which will lift the pull levers 52, from the pins 87 of the arms 31, and let down the push levers 53 in engagement with these pins, allowing the gears to be operated by the forward movement of the rack, while the said gears are raised out of engagement with the racks during their rearward movement. The operating lever is then drawn forward and the units wheel will remain stationary, as its pin 68 is against the under side of the units trip lever, but the spring dog 27, will trip its type lever, and print a naught on the record sheet. The tens wheel has been moved one tooth so that its pin 68 stands one tooth below the tens trip lever, and the tens rack will therefore move only one tooth, when it is stopped by the contact of the pin 68, with the under side of the tens trip lever, but its type bar will be tripped, as the cross bar moves on, and will print the figure 1, on the record sheet, thus giving the total 10. The remaining racks will remain stationary as their respective wheels have not been moved, and are locked by the engagement of their pins with the under sides of their respective trip levers, and thus all the wheels stand at zero, ready for another operation. As the cross bar returns, the push lever 53 will be lifted out of engagement with the gears, and the cross bar will push the tens rack to its normal position. The operation of the subtracting mechanism is substantially the same as the adding mechanism, except that the pins 68 stand above the inclined edges of the trip levers 69, of the subtracting mechanism, when the gears are at naught, for the reason that if one is to be subtracted from naught, I necessarily have to take one from the next higher order, and it is necessary in order to operate the subtracting mechanism that the subtracting mechanism be thrown in and the adding mechanism be thrown out, by operating the subtracting lever, as has been above described. Thus for example, there is a sum total in the machine of 14,000, from which we wish to subtract 5. The five key in the units row is depressed, and the operating handle drawn forward, and the units wheel will be reversed five teeth. Now the pins 68 in this instance, standing above the trip levers 69, will press all the said levers out against their latches 114, but not trip them. Now as the units wheel is reversed, it forces the trip lever against the adjacent trip latch, tripping it, and causing it to fly up, and its arm 119, will crowd between the lever and latch of the tens, which will in turn trip the hundreds slide, which will trip the thousands slide, the fifth slide or tens of thousands remaining stationary for the reason that its operating wheel stands at 1, and consequently its trip lever is not against the latch, and thus, as the arm 119, of the thousands latch

flies up, it will pass into the space between this said lever and latch, without affecting them. Thus the units wheel will be reversed 5 teeth by its rack, while the following three 5 wheels are reversed one tooth by the lifting of the gears by the push levers on the return of the operating lever, and the contact of the raised sliding bars with a rod 111A, which pushes them down to their normal position in 10 the cage, causing their respective pawl levers to reverse these three wheels one tooth, and to get the result the subtracting lever is pushed to its normal position, or so as to bring the adding mechanism into engagement with the gears, and the same operation is performed as when a total in addition is secured.

In order to automatically turn the platen roll to move the record sheet, a predetermined distance, after the printing of each line of figures, and at the same time wind the typeribbon intermittently from one spool to the other, I pivot in a bracket 124, a lever 125, which is normally held against the rear edge of the cross bar 28, by a spring 126. This lever is pivoted a short distance below its upper end, and to its upper end is pivoted the forward end of a forked arm 127, to the upper member of which is pivoted a spring 30 actuated pawl 128, which engages a ratchet wheel 129, secured to the end of the platen roll. The lower member of this forked arm carries a spring-actuated pawl 130, which engages the broad-faced ratchet wheel 10D, on the ribbon spool actuating shaft 10C. Now, as the cross bar is drawn forward the spring 126, will push the lever 125 forward, also, causing the arm 127 to move rearward and the pawls 128 and 130 to engage a tooth 40 of the respective ratchet wheels 129 and 10D, and as the cross bar returns to its normal position, it will contact with, and move, the lever 125 rearward, which will draw the arm 127 forward, and move the ratchets 129 and 45 10D each, one tooth, as will be readily understood by reference to Fig. 15. The arm 127 is supported on a roller 127A.

The type-ribbon is preferably a two-color ribbon, each color extending one half of the 50 width of the ribbon throughout its entire length, the half of the ribbon used in adding being blue, while the half used for subtracting is green. Now in order to shift this ribbon, when subtracting is done, I pivot near the upper end of the subtracting lever 103, an arm 131, which extends rearward to within a short distance of the rear end of the casing, and is pivotally connected to a rocking arm 132, the pivotal point of which is slightly 55 nearer its opposite end, which is slotted at 133, and is connected by a pin, with a sliding bar 134, which is forked at its forward end to provide ribbon guides 135, which are in the form of flat loops or eyes through which the ribbon passes, and they have openings on

their upper sides for the insertion of the ribbon. Thus, as the subtraction lever 103, is moved to bring the subtracting mechanism into operation, the arm 132 will be rocked, pushing forward the ribbon guide, and bringing the green half of the ribbon under the vertical center of the platen roll.

In order that the operating lever may always be moved to the limit of its forward movement, when started in that direction, or to the limit of its rearward movement, when started in that direction, I form on the bearing 34 on one side of the casing, a substantially semi-circular plate 136, having an upwardly projecting lug 137, extending vertically from its circumferential edge, on each side of which is a plurality of ratchet teeth, the teeth 138 on the forward side of the lug pointing rearward, while the teeth 138* on the rear side of the lug point forward.

Upon the adjacent rock lever 31, is pivoted a double pawl 139, having a tail which is engaged by spring dog 140. When the pawl is in engagement with one set of ratchet teeth, it is out of engagement with the other, and the spring dog operates first on one side of the tail and then on the other to hold the pawl in engagement with either one or the other of the sets. Now on the forward movement of the operating lever, the pawl is in position to engage the teeth 138A, and will thus prevent backward movement of the lever, but as the lever reaches its forward limit, the lug 137 will trip the pawl, and cause it to engage the teeth 138, which will prevent any forward movement, until after the lever has completed its full rearward movement, and this will obviate any disarrangement of the gears by a partial movement of the racks.

A correction key 48A is employed in connection with rod 48, which operates the locking plate latches 43, and this key is pressed to move out the said latches, unlock the plates, and allow any depressed keys to return to their normal position, when a wrong key has been unintentionally pressed and this operation will not affect any of the other mechanism.

While I have illustrated and described the preferred construction of my improved adding and subtracting machine, I do not wish to be limited to the construction and arrangement shown, as many changes might be made therein without departing from the spirit of my invention.

Having described my invention, what I claim as new and desire to secure by Letters Patent is:

1. In an adding and subtracting machine, the combination with a casing, a key-board of depressible keys, and a type-writing and recording mechanism, of a series of sliding racks spring-controlled to move into engagement with said keys of said key-board, means connected with said keys for locking and re-

leasing said sliding racks, a shaft in said casing; a manually reciprocating lever secured to said shaft, a pair of vertical rock arms secured to said shaft, a cross-bar extending across said sliding racks and connected to said rock arms by a pivotal connection, spring tripping dogs connected to said cross-bar arranged to engage the hook end of said type-bars to tilt them away from said printing mechanism, as the racks recede; spring-actuated arms for normally holding said dogs out of engagement with said type-bars, and springs for throwing said type-bars into printing relation with said recording mechanism; when said type bars are released by said spring tripping dogs.

2. In an adding machine, the combination with a supporting casing, a key board, having a plurality of rows of keys embracing the numerals from one to nine in each row, a type-writing mechanism co-operatively arranged with said key-board in said casing, each key having a notch in one side, a projecting stop on the other side, a reduced terminal end forming a shoulder, and a spring arranged to hold it in its normal position; a support for the keys, a hinged U-shaped tilting plate having one of its limbs arranged to lock a key of any of said rows of keys when it is depressed, and to lock the remaining keys of said row against depression, a spring for holding said U-shaped plate in and for returning it to its nominal position, when released from said key, a latch arranged to catch and lock said U-shaped plate in its key locking position when it is tilted down by the depression of said key, a spring arranged to control the locking movement of said latch, means for tilting said latch to release it from said key locking plate, a rock shaft mounted in said casing, a reciprocating operating lever secured to said rock shaft, a pair of rock arms secured to said shaft, laterally extending pins secured to the sides of said rock arms, pull and push levers arranged to be connected to said pins, and having their forward ends extending into contacting relation to said latch-tilting means, and means for simultaneously lifting one set of levers out of engagement with the pins of the rock arms, and for dropping the other set of levers into engagement with the said pins.

3. In an adding and subtracting machine, the combination with the casing, the type-writing mechanism, and the key-board, having the keys arranged in successive step order, of sliding racks having stepped edges arranged to engage the keys of said key board; locking plates for said racks; latches for said locking plates; a rod for swinging said latches, and means for depressing said rod; a reciprocating operating lever; rock arms operated by said levers; pull and push levers arranged to be connected with or disconnected from said rock arms and extended

into engaging relation with the rod depressing means for said latches; a shaft having gear wheels, which are engaged by the sliding racks, and means connected with the push and pull levers for lifting the said shaft to disengage the gears from the racks.

4. In an adding machine, the combination with the casing, the numeral key-board, and a recording mechanism, of sliding racks, each comprising a vertical arm, an upper horizontal arm, a lower horizontal arm extending rearward in said casing and having gear teeth, and a horizontal arm extending forward into the operative field of said key board, one edge of which is provided with a series of steps; rollers arranged beneath said sliding racks, said keys being provided with stops arranged in operative engaging relation to the shoulders of said steps on said sliding racks; stops arranged to normally prevent the engagement of said sliding racks with said keys, means for releasing said sliding racks from said stops when a key is depressed, and means for locking the keys in a depressed position and for releasing them; a cross bar in normal engagement with the sliding racks; springs arranged to normally hold said sliding rack against said cross bar, means including a reciprocating operating lever for releasing said cross bar to allow the said sliding rack to move forward by its spring, so that one of its stepped shoulders may engage a depressed key, type-bars pivoted to said sliding racks; and means connected to said sliding racks and cross bar for causing said type-bars to print the numerals corresponding to the depressed keys.

5. In an adding and subtracting machine, the combination with a casing, a key-board, and a type-printing mechanism, of a plurality of sliding racks co-operating with said key-board, and with said printing mechanism, a spring for drawing each sliding rack toward each key of said key board, means including a lever mechanism for releasing said sliding racks, means including a key locking device comprising a hinged tilting plate with said keys for preventing the forward movement of said sliding racks when said keys are not depressed, and means for releasing said sliding rack when a key is depressed, and for locking said key in a depressed position, means including a reciprocating lever connected to said operating lever for releasing said keys and for restoring said key-board and sliding racks to their normal positions, numeral type carrying bars on said sliding racks arranged in operative relation to said printing mechanism, a spring controlled trip lever supported to said casing arranged to normally hold each of said type bars in a position of disuse, a spring arranged to actuate said type bars to print a numeral, and means including a trip spring connected with said operating lever mechanism for re-

leasing said trip-lever and for actuating said type bars to print a numeral.

6. In an adding and subtracting machine, the combination with the casing, and the numeral key-board, comprising a plurality of rows of keys, of a tilting frame, a shaft rotatably mounted in said frame, a plurality of gears rotatably mounted on said shaft, a pair of levers, arranged adjacent to the opposite ends of said shaft, each pair comprising a pull and a push lever, arms on said levers spring controlled in one direction of their movement, arranged to engage said shaft on the operating movements of said lever and lift the same; sliding racks, which engage said gears; a shaft having rock arms which operate the pull and push levers, and a crank handle for operating the said shaft.

7. In an adding and subtracting machine, the combination with the casing, a printing mechanism, a key-board, and a plurality of sliding racks each having a type bar pivoted thereto, of a shaft mounted across said casing, a frame comprising two side plates pivotally mounted at their forward ends to the opposite ends of said shaft; a shaft mounted in the opposite ends of said frame, gears loosely mounted on said shaft corresponding in number to the number of rows of keys on said key board, said gears being normally in engagement with the sliding racks, means including pull and push levers for lifting said gears out of engagement with the racks, a shaft having rock arms which operate said levers, and a crank handle for operating said shaft.

8. In an adding and subtracting machine, the combination with the casing and key-board mounted on said casing, of a plurality of sliding toothed racks, a type-bar operatively supported on each sliding rack, each type-bar being provided with a row of numeral types arranged in successive order from zero to nine, a gear carrying frame consisting of two side plates arranged on opposite sides of said casing, pivotally secured at one end to said casing, and resting on said casing at their opposite or free ends, a shaft extending across the free ends of said side plates and extending beyond them, a row of gears rotatably mounted on said shaft, which are normally in engagement with the toothed racks, springs for operating said racks in one direction; a cross bar for operating the racks in an opposite direction, and a hand operating reciprocating lever for operating the cross-bar.

9. In an adding and subtracting machine, the combination of the casing, the key-board, the type-printing mechanism, and the hand operating lever, with a pair of rock arms within said casing arranged to be actuated by said operating lever, a pair of arms slotted at one end and pivotally connected 65 at their slotted ends to said rock arms, a cross

bar pivotally connected at its ends to the opposite ends of said slotted arms, sliding racks, spring-operated in one direction, and operated in the opposite direction by the said cross bar, contraction springs arranged to normally hold said cross bars against said racks; gears engaged by the racks; means connected with the rock arms for lifting the gears from the racks; the slots in said slotted arms permitting a sufficient movement of the lifting means, to lift the gears from the racks before the said racks are moved.

10. In an adding and subtracting machine, the combination of the casing, the key-board, the type-writing mechanism, and the actuating rock arms having projecting pins, of a pair of push levers arranged one on each side of said casing on one side of each of said actuating rock arms, a pair of pull levers arranged one on each side of said casing on the opposite side of each of said rock arms, each of said levers being provided with a recess adapted to engage the projecting pins of said actuating levers, means for slidably supporting the rear ends of said push and pull levers, a shaft having a plurality of gears; sliding racks normally in engagement with the gears, means connected with each pair of push and pull levers for engaging the ends of said gear-shaft and for raising said gear supporting frame and gears out of engagement with said toothed racks at a predetermined movement of said levers.

11. In an adding and subtracting machine, the combination of the casing, the key-board, the type-writing mechanism, the sliding racks, the operating lever, the actuating rock arms, having lateral pins, the cross-bar, the gears, and the pull and push rods, which engage the pins of said rock arms, with a pair of gear operating frames mounted on opposite sides of said gears, a tilting frame secured and arranged to support said frames, a pair of connecting rods connecting said frames together, a rocking lever for engaging the under side of said pull and push levers, to raise or lower them out of or into engagement with the pins of the rock arms, a shaft extending across said casing adjacent to its rear end, and secured in the sides of said casing, a pair of crank-arms secured to said shaft, a pair of levers connected at one end to the free ends of said cranks and at their opposite ends to an arm connected at one end to said pull and push levers' rock-lever; a rock arm at the forward end of said casing pivotally connected to the opposite end of said arm, a slot in said second named arm pivotally connected to a connecting pin of said pull and push lever's rock-arm, a push lever connected at one end to one of said connecting rods of said frames and pivotally connected intermediate of its ends to said pull and push lever rock arm, and having its free end extend to and ar-

ranged to engage the free end of a depending arm on the said forward rock arm shaft.

12. In an adding and subtracting machine, the combination of the casing, the key-board, the type-writing mechanism, the hand operating and actuating lever mechanism, the subtracting mechanism, operating lever, and the pull and push rods and the gears supporting tilting frame and shaft, the gear operating frames, and the gears, with a plurality of vertically sliding plates in each of said gear operating frames, a plurality of four pins secured at the quarter joints of each of said gears, a swinging pawl on each sliding plate arranged to be engaged by said pins as said gears are rotated, a vertically impulse action lever spring-controlled in one direction of its movement, arranged to be normally locked to said frames and adapted to be released by said swinging pawl plates, and the rotative movement of said gears, and to be impinged against said crank-shaft by their springs when released, by the movement of said gears and said swinging pawl-plate, and a swinging pawl pivotally secured to each of said impulse levers of each gear operating frame arranged to engage the teeth of said gears, arranged to be normally locked out of engagement with said gear teeth.
13. In an adding and subtracting machine, the combination of the casing, the numeral key-board, the type-printing mechanism, the sliding racks, the operating lever, the actuating lever and cross bar, the adding mechanism, comprising the gears, the gears supporting shaft, the tilting frame, and the pull and push rods, with the two opposing gear operating frames arranged on opposite sides of said gears, the connecting rods arranged to connect said frames together, the subtracting mechanism operating lever connected to said connecting rods, a laterally projecting pin on one side of each gear, and an operative gear rotating mechanism arranged to rotate each gear one or more teeth in alternate order by either of said gear operating frames as either one of said gear operating frames is moved into operative relation to said gears and the other is moved out of operative relation to said gears by said subtracting lever.

14. In an adding and subtracting machine, the combination with the casing, the key-board, the type-writing mechanism, the sliding-racks, the gears engaging said sliding racks, and type-bars, and the operating and actuating lever mechanism, of the subtracting mechanism comprising the gear operating frames arranged on opposite sides of said gears, the connecting rods, the subtracting lever, said frames being provided with a plurality of slots at their upper end, a rod across their lower ends, a group of sliding levers slidably supported in said slide-ways, and by said rods, a group of swinging plate-levers

pivoted to said levers, a laterally projecting pin on each quarter point of one side of each gear arranged to engage said plate-levers, a group of levers each carrying a right angled arm extending into the path of the lever plate of the adjacent sliding lever, and each provided with a gear tooth engaging pawl arm, arranged to be normally held out of engagement with the teeth of said gears, a spring for raising said pawl carrying levers and pawls into operative position, and an engaging abutment adapted to hold said levers and pawls and cause them to engage said gears operatively and rotate them as said gears and their supporting frames are raised by said operating lever.

15. In an adding and subtracting machine, the combination with the key-board, the type-writing mechanism, the sliding racks, the numeral type carrying bars supported by said sliding-racks, the operating lever, the sliding racks actuating mechanism, the tilting frame, and shaft, the gears mounted on said shaft and normally in engagement with said sliding racks, the actuating levers, and the push and pull levers operatively arranged to be actuated by said operating lever to raise said gears out of engagement with said racks on either its forward or rearward stroke, of the two gear operating frames comprising the numeral adding and subtracting mechanism arranged on opposite sides of said gears, pivotally hinged to said tilting frame to be tilted therein, and a hand operating lever arranged to tilt either of said frames either into or out of engagement with said gears, as it is desired to add or subtract.

16. In an adding or subtracting machine, the combination with the casing, the gear supporting frame, its shaft, and the seven gears mounted on said shaft, of a numeral adding frame, and mechanism arranged on the front side of said gears and pivoted in said gear supporting frame, the numeral subtracting frame, and mechanism pivotally hinged in said gear supporting frame on the rear side of said gears, said frames being connected together to be tilted toward and from said gears, a lever connected to said frames and arranged to tilt them toward and from either the front or rear side edges of said gears, projections at the four quarters of one side of said gears, and means including a system of sliding levers and swinging levers and pawls mounted in and carried by said frame and arranged to be actuated by the projections on said gears for operatively rotating said gears to add or subtract, as desired.

17. In an adding or subtracting machine, the combination with the casing, the operating lever and sliding-racks, the actuating levers, the gears and their supporting shaft and tilting frame, and the key-board and printing mechanism, with a pair of gear operating frames arranged on opposite sides of

said gears and tiltingly supported in said gear tilting and supporting frame, a sliding lever slidingly mounted in each frame opposite each gear, a swinging pawl pivotally connected to one side of each sliding lever, and projecting along the side of each gear, projections at the four quarter points of each of said gears adapted to engage one surface of said swinging levers and to move them out of their path, on one direction of said gear's rotary movement, and to abut against another surface of said swinging levers in the opposite direction of said gear's rotary movement, a trip lever arranged in each of said frames in operative relation to each of said gears and spring-controlled in one direction of its movement, a swinging pawl pivotally connected to each of said trip levers in operative relation to the teeth of each of said gears, and arranged to be normally locked out of engagement with the teeth of each gear, an arm on each trip lever projecting from the predetermined or units side of said frames or trip lever into the path of the next trip lever, and arranged to trip the same and all of said trip levers in successive order, an abutment against which said trip levers strike when released from said frames, and a spring arranged to throw each trip lever against said abutment.

18. In an adding and subtracting machine, the combination with the casing, the gear supporting and tilting frame, the shaft extending there-through, and the gears mounted on said shaft representing units, tens, hundreds, and higher orders from one end of them to the other, with the numeral adding and subtracting mechanism, comprising a pair of supporting frames pivotally attached to said gear supporting and tilting frame, and arranged on opposite sides of said gears, and connected with each other, a hand operating lever arranged to tilt said frames toward and from said gears in alternate order, a plurality of sliding levers opposite each of said gears arranged to slide vertically in said frames a predetermined distance and representing units, tens, hundreds, and higher orders from one end of said levers to the opposite end, projections on the one side edge face of each gear at its quarter points, a swinging plate lever on said sliding bars having terminal ends extending in opposite directions, one end of which is beveled downward and is spring-controlled to lie in the path of said gear's projections, and is adapted to be engaged by said gear's projections, and be moved a predetermined distance in one direction of said gear's rotative movement, and the terminal end of which forms a stop for said gear's projection on the opposite rotative movement of said gears, and the opposite terminal end of said lever extends in an opposite direction from said gear engaging end and is provided with a right-angled offset arm, a vertically arranged trip lever pivotally connected at its lower end to the lever side of each vertical sliding lever, having its upper ends arranged to said supporting frame, each of said trip levers being arranged in the path of said swinging gear rotating plate lever's right angled arm end, a contraction spring arranged to hold said trip levers under a vertical moving tension, a swinging pawl lever pivotally connected to each having a right-angled extending pawl arm arranged in tooth engaging relation to the gear teeth of each gear, means including an extending arm on each pawl lever for normally holding all of said pawls out of engagement with said gear teeth, a right-angled arm on each of said trip levers extending from said unit trip arm to the tenths trip arm and from the tenths trip lever to the next trip lever and so on to the end of said row of trip levers, said arms being arranged between the adjacent trip lever and the angled arm of said spring controlled swinging gear operating lever of each sliding lever, an abutment in the vertical path of said sliding levers adapted to receive their vertical impulse when said trip levers are released, and adapted to hold said sliding levers and the swinging gear operating levers and the pawl levers in gear wheel rotative relation to said gears when said gears are raised in the supporting tilting frame to carry one or more numerals from the units or tenths or other gears or to subtract them from said gears, as specified.

19. In an adding and subtracting machine, the combination of the casing, the key-board, the printing mechanism, the sliding racks, the tilting gear supporting frame and gears and the two operating levers, with the tilting numeral carrying and subtracting mechanism comprising the tilting frames pivotally and tiltingly supported in said gear supporting and tilting frame, the vertically sliding levers, the trip levers pivotally secured to said sliding levers and spring controlled to vertically raise said sliding and trip levers, an abutment shaft extending across said casing arranged to receive the upward impulse movement of said sliding levers, the gear teeth engaging pawls on said trip levers, the spring controlled swinging levers on said sliding levers, the projecting pins on each of said gears, the curved depending extensions on said pawl levers, and the shafts across said casing arranged to be engaged by said curved extensions and to normally hold said pawls out of engagement with said gear teeth, and means for tilting said adding or subtracting mechanism and its supporting frames to throw either one of them out of or into engagement with the opposite sides of said gears as desired, and means for raising said gears' supporting frame out of said sliding racks to cause said adding or subtracting

mechanism to operatively rotate said gears to carry or subtract a number as desired, and for lowering said gears into said racks.

20. In an adding and subtracting machine, the combination of the casing, the units, tens, and higher orders of gears, the supporting and tilting frame for said gears, with the numeral carrying mechanism, comprising a frame consisting of end pieces pivotally secured at their lower ends to said gear supporting frame, a cross shaft extending from one end piece to the other having a plurality of reduced neck portions arranged at a predetermined distance apart, and two side pieces at their top end arranged at a short space apart, a plurality of slots in said side pieces, a plurality of vertically sliding levers slidingly arranged in said slots and having a slot in their lower ends adapted to fit the neck portions of said shaft, said sliding levers designating units, tens, hundreds, and so on to their end lever, arranged opposite side units, tens, hundreds, and higher order of gears, a trip lever pivotally secured at its lower end to each sliding lever and having a shouldered step at its upper end arranged to fit under the adjacent side piece of the top of said frame, a contraction spring arranged to hold said trip lever's shoulder up against the side piece of said frame thereby normally locking said trip levers, and said sliding levers, under a vertical movement tension to said frame, the swinging plate levers pivotally secured to said sliding levers, the projecting pins on said gears, the pawl levers on said trip levers adapted to engage said gear teeth, the shafts and projecting curved ends on said pawl levers for normally locking said pawls out of engagement with said gear teeth, the abutment shaft arranged to receive the vertical impulse movement of said sliding levers and trip plates, and the angled arms on said trip levers arranged to trip all of the remaining trip levers of a higher order in said frame.
21. In an adding and subtracting machine, the combination with the casing, of a shaft mounted transversely thereon, a frame comprising two plates pivotally connected at one end to said shaft at opposite portions of said casing, and arranged to rest loosely at their opposite ends on said casing, a shaft extending across the rear ends of said plates, a plurality of gears loosely mounted on said shaft representing in succession the numeral orders of units, tens, hundreds, and so on to as high an order as desired, from one side of said shaft to the other, a plurality of sliding racks corresponding in number to the number of gears in which said gears are in operative mesh, means including a hand operating lever for raising said gears out of mesh with said sliding racks when desired, an operative gear tooth engaging pawl mechanism on opposite sides of each of said gears arranged to
- cooperate with said sliding racks to rotate said gears one or more teeth as desired, means for normally holding one of said pawl mechanisms in engagement with one side of each of said gears, and means including a hand operating lever for moving said normally engaged pawl mechanism out of engagement with said gears and for throwing the opposite pawl mechanism into engagement with the opposite side of each of said gears.
22. In an adding and subtracting machine, the combination with the casing, of the key-board provided with a key-board of preferably seven rows of numeral keys, each row containing keys from one to nine, a plurality of sliding-racks corresponding in number to the number of rows of keys, a plurality of preferably seven type-bars positioned one on each sliding rack, a plurality of preferably seven gears representing in successive order units, tens, hundreds, thousands, tens of thousands, hundreds of thousands, and millions, arranged to stand normally in mesh with said sliding racks, means including an operating lever and a supporting tilting frame for raising said gears out of engagement with said sliding racks, when desired, a gear tooth pawl engaging mechanism arranged in operative relation to each side of each of said gears, one pawl mechanism of which is arranged to stand normally in engagement with one side of said gears, and the other pawl mechanism to stand normally out of engagement with the opposite side of said gears, means including a tilting supporting frame for said pawl mechanism and a hand operating lever for moving the normally gear engaging pawl mechanism out of engagement and for moving the opposite pawl mechanism into engagement with said gears, and projections on each gear at predetermined points arranged to coöperate with said pawl mechanism to carry or subtract numerals or numbers on said gears.
23. In an adding and subtracting machine, the combination with the casing, and a fixed numeral key-board, with a plurality of sliding rack levers actuated by the keys of said key-board a hand operating lever arranged to operate said rack levers, and type bars, each provided with a set of numerals from 0 to 9, inclusive, said type-bars being arranged relative to the printing point of said printing mechanism so that the 0 of each type-bar stands normally at the printing point, and means including operating lever and a spring-controlled trip mechanism for causing said type-bars to move into printing relation to print any numeral desired when its numeral key is depressed.
24. In an adding and subtracting machine, the combination with the casing, the key-board, the printing mechanism, the sliding racks, the type-bars actuated by said sliding

racks, the hand operating lever, the actuating lever, and the mechanism connecting this actuating lever with said sliding rack and co-operating with the keys of said key-board to 5 actuate said type bars and printing mechanism with the pull and push levers, the tilting numeral carrying and subtracting gears arranged to normally stand in engagement with said sliding racks, and its supporting 10 and tilting frame, and the gear supporting shaft, the oppositely arranged spring-controlled arms arranged on said pull and push rods to engage said gear supporting shaft and to raise said shaft and gears and their supporting frame out of engagement with said rack.

25. In an adding and subtracting machine, the combination with the casing of the type-writing mechanism, and the key-board, comprising a plurality of rows of numeral keys containing numerals from one to nine, and a totaling key and a correcting key, a support for said keys, resilient means for holding each key in a vertical position of disuse, a shoulder in one side of each of said numeral keys adjacent to its terminal end, a notch in said side of each key adjacent to said shoulder, a projecting lug on the opposite side of said key adjacent to its terminal end, a hinged tilting 30 open-sided box-shaped lock plate arranged to support against its lower side member the terminal ends of said keys and arranged so that when tilted its upper side member will extend into the slot of any one key of each 35 row that is depressed and thereby lock said key in a depressed position, and also arranged to extend under the shoulders of all of the remaining keys of each row of keys in which a key has been depressed, and means 40 including a rock arm spring controlled in one direction of its movement for locking said tilting plate in a depressed position and for releasing all of said keys, and for returning all of said depressed keys to their nominal 45 operative position.

26. In an adding and subtracting machine, the combination with the casing of the operating levers, the actuating levers having lateral projecting pins on each side of each lever intermediate of their ends, the gear tilting and supporting frame, of a pair of pull levers containing a slot adapted to fit on the pins, of one side of said actuating levers, said pull levers extending to the rear end of said casing 55 and containing in their rear ends a slot, pin containing neck grooves arranged to receive the slots and support the rear ends of said levers, a tilting frame pivotally secured in said casing, a shaft in said frame, a plurality 60 of numeral carrying gears rotatably mounted on said frame, a plurality of sliding racks normally in engagement with said gears in said casing, a lever pivotally connected to each of said pull rods, arranged to stand normally at 65 an angle, and with its free end adjacent to

the opposite ends of said gear supporting shaft, each of said levers being provided with a beveled top level with the top of said levers, a stop for defining the operative shaft engaging position of said shaft engaging lever, a spring for returning said lever to its operative slot engaging position, after operative use, a clip pivoted to said lever at one end and extending above said lever and having a concaved terminal end adapted to engage said shaft, and an angled clip extending around said lever, a spring for moving said clip back into its shaft engaging position after operative use, said shaft engaging levers and clips being adapted when said hand operating 75 lever is moved toward the operator to draw said pull levers toward the front of the machine and in doing so to cause said shaft levers and clips to engage the opposite end portions of said shaft and to lift said gears 80 out of engagement with said racks, and as the pull levers move onward said levers and clips pass under said shaft and slip off of it allowing said shaft and gears to drop back into engagement with said sliding racks. 90

27. In an adding and subtracting machine, the combination with the casing, the sliding racks, the operating lever, the actuating levers, the tilting gear supporting frame, the gear supporting shaft and the gears, of 95 the pull rods, removably connected to said actuating levers, the shaft lifting levers pivotally secured to said pull rods, and the shaft lifting clip arranged to engage said shaft on the forward movement of said levers and to 100 lift it and slip off of it as they pass under said shaft, and stops and springs arranged to return said levers and clips to their normal shaft engaging position.

28. In an adding and subtracting machine, the combination with the casing, the key-board, the sliding rack having a stepped extension, of as many steps as there are keys in each row of keys on said key-board, arranged to coöperate with the keys of said key-board, a hand operating lever for releasing said sliding rack, a spring on each sliding rack, a cross-bar arranged to hold said sliding racks in alinement, a lock plate for locking said keys in a depressed position and for preventing the remaining keys from being depressed, a stop on each key arranged to receive the corresponding step of its sliding rack, and means for instantaneously releasing all of said keys and returning them to 115 their natural positions. 120

29. In an adding and subtracting machine, the combination with the key-board, the type-printing mechanism, the totaling key, the correcting key, the operating levers, the 125 sliding rack, the numeral carrying gears normally in engagement with said sliding-rack and arranged to be moved out of engagement with said sliding racks, means including the pull and push levers and said actuating le- 130

vers for operating said gears, the oppositely arranged pawl mechanism for rotating said gears to add or subtract a numeral, means including levers arranged in operative relation to said totaling key, a tilting frame arranged to support the said gear adding and subtracting pawl actuating mechanism, a hand operating mechanism for throwing said numeral adding mechanism or said subtracting mechanism, into engagement with said gears as desired, rock-arms operatively connected to said pull and push levers and with said gear rotating pawl mechanisms tilting and supporting frames, and also with said totaling keys operating mechanism for totaling amounts registered by said gears, a plurality of type-bars operatively controlled by said sliding racks, a continuously feeding paper in said printing mechanism, and means including a swinging rod for correcting all of the keys of said key-board.

30. In an adding and subtracting machine, the combination with the key-board, the lock plate, the operating lever, and the pull rods, of a correcting key operatively positioned therein, and spring-controlled on its operative movement and provided with an oblong slot at its lower terminal end, a rod extending transversely across said casing and 35 extending through said oblong slot, angled arms secured at one end to said rod and secured at their opposite ends to a shaft journaled in the sides of said casing, and a plate on the opposite end of said angled arms arranged in the path of and adapted to be struck by the adjacent ends of said pull rods on their forward stroke, and means connected with said rod and correcting key and including an angled rock-arm adapted to 40 engage said lock-plate for correcting said key-board.

31. In an adding and subtracting machine, the combination with the casing, the key board, the sliding racks, and the type bars, of an operative ink feeding ribbon, a type-striking roller, a continuous roll of paper, and means for feeding said paper continuously from said roll of paper between said ink ribbon and said type-striking roller.

50 32. In an adding and subtracting machine, the combination with the casing, the key-board, the type-writing mechanism, the series of seven sliding-racks, the operating lever and the actuating levers, of a series 55 of seven type-bars pivotally secured to said sliding racks, each of which is provided with a row of numerals from 0 to 9, a spring secured at one end to each sliding rack and at its opposite end to each type bar, and 60 adapted to throw each type bar against said printing mechanism, a hook at the rear end of each type bar, a series of seven rock-arms, one for each type-bar, pivotally supported on a shaft in said casing, having one arm

normally in engagement with the hook of 65 each type-bar and having its opposite arm connected to a contraction spring, a shoulder in the type-bar hook engaging end of said rock-arm, a projecting lug on each sliding rack normally in engagement with said shoulder, a cross bar extending across said casing, connecting rods extending from the opposite ends of said cross bars to said actuating levers and having a slotted pivotal connection with said actuating levers, a contraction spring between said cross bar and each of said actuating levers, and a spring hook for each type bar, each of which is connected at one end to said cross-bar and extending into engagement with the type bar 75 hook engaging end of said rock-arm and in engaging relation to the hook of each type-bar, and a right-angled arm on each rock-arm extending from the units rock-arm or from the rock-arm farthest to the right 80 hand in the casing to lap over and on top of the end of the next or tens or adjacent rock-arms hook engaging end of this tens rock arm, and so on to the last or millions rock-arm of the series.

33. In an adding machine, the combination with the casing of the key-board and the type-writing mechanism, of the sliding racks, the spring-controlled trip rock-arm, the cross bar, the actuating levers, the connecting rods extending from said actuating levers to said cross bar, and having a compensating moving pivotal connection with 95 said actuating levers, the hand operating lever, the spring hooks on said cross bars arranged to engage said typewriting mechanism, and the lugs on said sliding racks arranged to engage said trip rock-arms.

34. In an adding and subtracting machine, the combination with a platen roll, and a type-ribbon beneath said record sheet, of spring-actuated racks having pivoted type-bars thereon; springs for normally holding said type-bars out of engagement with the type-ribbon; a cross bar in normal engagement with the racks; spring dogs carried by the cross bar for engaging depending ends of the type bars, spring-actuated arms which normally prevent said dogs from engaging the type-bars; fingers on said racks 105 which lift said arms as the racks recede and permit the dogs to engage the type-bars; means for stopping said racks at a predetermined point, whereby a further movement of said cross bar causes said dogs to trip the type bars and imprint numerals on the record sheet; means in connection with the cross bar for rotating said platen roll and ribbon step by step simultaneously, and a hand lever for operating the cross bar.

35. In an adding and subtracting machine, a plurality of sliding racks; gears engaged by said racks, having laterally project-

- ing pins; adding and subtracting mechanisms interchangeably engaged by said gears; type-bars carried by said racks; a platen roll and record sheet in operative relation to said 5 type bars; a type-ribbon beneath the record sheet; means for tripping said type-bars when the racks recede; a lever for simultaneously throwing the adding mechanism into engagement with the gears, and the subtracting 10 mechanism out; a sliding support for said type-ribbon, and means connected with the lever and with the sliding support, for moving said support at right angles to the length of the ribbon.
36. In an adding and subtracting machine, the combination with a platen roll, a record, and a type-ribbon beneath said sheet, of a plurality of sliding racks, each having a type-bar pivoted thereto; springs for holding 20 said type-bars in a predetermined position relative to the ribbon; a cross-bar, spring-controlled in one direction of its movement, which normally rests against said racks; spring dogs upon said cross bar adjacent to depending ends of said type-bars; spring-actuated arms above said dogs which normally prevent them from engaging the depending end of the type bars; a projection on each of the spring-actuated arms, which 25 overlies and rests upon the adjacent arm; fingers upon the racks which lift the said arms as the racks recede, and permit the dogs to engage the depending ends of the type-bars; a lever for moving the cross bar away from said racks; springs for moving 30 the racks in the direction of the cross bar, and means for stopping the racks at predetermined points, whereby a further movement of said cross-bar will cause its dogs to trip the type-bars and imprint numerals upon the record sheet.
37. In an adding and subtracting machine, a plurality of sliding racks having pivoted type-bars, and springs for holding said bars in a predetermined position; a cross-bar, spring-controlled in one direction, which abuts against the racks; spring dogs upon 45 said cross bar, which lie adjacent to depending ends of the type-bars; spring-actuated arms, which normally prevent the dogs from engaging the depending ends of the type-bars; fingers on the racks which lift the arms as the racks recede, and permit the dogs to engage the depending ends of the type-bars; 50 means for lifting one or more arms on one side of an arm raised by one of the racks, comprising projections, one of which is formed on each arm so as to overlie and rest upon the adjacent arm; a lever for moving the cross-bar and springs for moving the racks in the direction of the cross-bar.
38. In an adding and subtracting machine, a cross-bar, spring-controlled in one direction; a plurality of sliding racks abut- 55
- ting against said cross-bar and spring-controlled in an opposite direction, the tension on said cross-bar being greater than that exerted upon the racks; pivoted type-bars carried by the racks, spring dogs carried by the cross-bar for engaging depending ends of the type-bars; arms which normally prevent the dogs from engaging the type-bars; fingers carried by the racks for lifting the arms as the racks recede, to permit the dogs to engage the type bars, and means for lifting one or more arms on one side of a predetermined arm which has been lifted by the movement of its operating rack, when the operating racks of said one or more arms remain stationary, consisting of a projection on each of 8 said arms, each of which overlies and rests upon the adjacent arm.
39. In an adding and subtracting machine, a plurality of sliding racks; a like number of gear wheels operated by said racks, having laterally projecting pins; adding and subtracting mechanisms which are interchangeably operated by said gears, each comprising a plurality of vertically movable, spring-operated bars, carrying a trip lever, a latch, and a pawl lever, the pins of said gears, in their initial positions, being beneath the trip levers, when the adding mechanism is in operative position, while the diametrically opposite pins are above the trip levers of the 95 subtracting mechanism, when it is in operative position.
40. In an adding and subtracting machine, a plurality of gear wheels, having projecting pins spaced ten teeth apart; adding and subtracting mechanisms, interchangeably operated by said gears, each comprising a plurality of vertically movable spring-actuated bars; a trip lever on each of said bars in the path of the gear wheel pins; a latch on 100 each bar, in position to be tripped by its trip lever and release the bar; a pawl lever on each bar in position to engage the next gear wheel; an arm on each latch which extends between the trip lever and latch of the adjacent bar; racks for rotating the gears; means for lifting said gears and mechanisms, to free said gears from said racks; and means for returning the released bars to their normal positions when said gears and mechanisms are 105 lifted, thereby causing the pawl lever of each released bar to engage the next gear wheel, and move it one tooth.
41. In an adding and subtracting machine, a plurality of gear wheels; adding and subtracting mechanisms, interchangeably operated by said gears; racks, spring-operated in one direction for rotating the gears; lock plates for holding said racks in their initial positions; keys for depressing the lock plates to release the racks; stops on said keys for limiting the movement of the racks; a platen roll, a record sheet, a type ribbon, and 125

means for moving said roll and ribbon simultaneously step by step; type-bars carried by the racks, and means for tripping them, when racks are stopped, causing them to imprint numerals upon the record sheet; a spring-actuated cross-bar for restoring the racks to their normal positions; a lever for moving the cross-bar in a counter direction;

and means for disengaging the gears from the racks during either movement of the lever.

In testimony whereof I affix my signature in presence of two witnesses.

JOHN C. EPENETER.
